PULLEY MECHANISM.

1,168,198.

Specification of Letters Patent.

Patented Jan. 11, 1916.

Application filed April 7, 1914. Serial No. 830,136.

To all whom it may concern:

Be it known that I, BENGT M. W. HANSON, a citizen of the United States, residing at Hartford, in the county of Hartford and 5 State of Connecticut, have invented certain new and useful Improvements in Pulley Mechanism, of which the following is a specification.

This invention relates to pulley mechanism, the object of the invention being the 10 provision of simple and effective means by which a pulley can be brought into proper relation with a companion pulley irrespective of the size of the latter.

15 In the drawings accompanying and forming part of the present specification I have shown in detail one of the several convenient forms of embodiment of the invention, which to enable those skilled in the art to 20 practise the same will be set forth fully in the following description. I do not restrict myself to the details of this disclosure; I may depart therefrom in several respects within the scope of the invention defined by 25 the claims following said description.

Referring to said drawings: Figure 1 is a vertical sectional elevation of pulley mechanism involving my invention. Fig. 2 is a transverse section on the line 2—2 of Fig. 1. 30 Fig. 3 is a side elevation of an arrangement of pulleys employed in connection with a metal working machine and involving my invention. Fig. 4 is a view as seen from the right in Fig. 3.

35 Like characters refer to like parts throughout the several figures of the drawings, which it will be noted are on different scales.

It is the custom now to use electric motors 40 for driving certain kinds of machinery. An electric motor is generally provided with a pulley which serves as a driver, the driven pulley constituting a part of the machine. Also as a part of such a machine is an idler 45 or intermediate pulley; there may in fact be several of such intermediate pulleys or idlers which are also a permanent part of such a machine. When such a machine is set up it is frequently found that the idlers 50 are not in proper relation with the driver or motor pulley, the consequence being that the pulley of the motor must be changed or different size idlers provided. I provide a construction by which this disadvantage is 55 eliminated, the organization being such that

the idler or one of them, if there be a plurality, can be shifted into proper relation with the driving pulley, so that the belt can correctly and accurately pass from the driver to the adjustable idler. The foregoing is merely one use to which the invention can be put, said invention not being restricted in this particular but covering broadly the adjustment of a pulley whether it be an idler or intermediate or one of some other 60 character.

Referring now more in detail to the drawings and especially to Fig. 3, the numeral 2 designates an electric motor and 3 its pulley which as will be clear constitutes the driver 70 for the driven pulley 4. As shown the axes of the driving and driven pulleys are at right angles to each other, but this is not a matter of consequence, nor is it essential that the driving pulley 3 constitute part of 75 an electric motor 2, the invention not concerning such details. Between the driving and driven pulleys 3 and 4 is the belt 5 which passes over the idler or guide pulleys 6 and 7, the invention residing in means 80 whereby the pulley 7 or its equivalent can be adjusted in such way that the belt 5 will be disposed properly with respect to the pulley 3, this disposition ordinarily being a 85 tangential one. Initially the axes of the 85 pulleys 6 and 7 are coincident, but the pulley 7 can be so tipped as to bring its axis of rotation at an angle to the permanently fixed axis of the pulley 6 at opposite sides thereof. The pulley 4 may drive any suitable 90 part for instance the vertical spindle of a grinding-machine.

The two pulleys 6 and 7 disposed opposite each other or side by side, are sustained by the bearing member 8 which as illustrated 95 consists of a plate, conveniently fastened as by one or more screws as 9 to the framework 10 of the machine with which the pulley mechanism is associated. Projecting from this bearing member 8 and 100 constituting a part thereof is the boxing 11 which directly supports the shaft 12 of the idler 6, the latter being rotative on the shaft 12 which may be secured in place in any desirable manner, for instance by the pin 13. 105 This shaft 12 extends through the hub 14 of the boxing 11, furnished with a lubricator 15 for said pulley 6. The pulley 7 is rotatively supported by the shaft 16 which as shown has a square inward extension 110

18 fitting flatwise for sliding movement against the opposite flat faces of the chamber 19 of the boxing 11, the outer flat face or wall of said chamber being formed upon 5 the removable plate 20 of the boxing which as shewn is held in place to the body thereof by several screws 21. It will be clear that the extension 18 and therefore the pulley 7 can be tipped or tilted to vary the angle of 10 presentation of said pulley 3 or one of an equivalent character. For holding the pulley 7 securely in an adjusted position and for maintaining it in such relation, any desirable means may be provided, although 15 those shown and now to be described have been found satisfactory. Tapped through what is shown as the bottom wall of the boxing 11 are the screws 22 and 23, while tapped through the upper wall of said boxing is the screw 24, the two screws 22 and 23 engaging one face of the extension 18 while the screw 24 engages the opposite face of said extension, the screw 24 being located between the screws 22 and 23; that 25 is to say the three screws are approximately triangularly arranged. The pulley 7 is shown as occupying its initial or original position in full lines in Fig. 1 and as occupying its shifted or adjusted position by 30 dotted lines in the same view. To shift the pulley 7 from the full line to the dotted line position, the following procedure may be adopted: The screw 22 will be backed out the requisite distance, so that the extension 35 can follow the same and swing on the inner end of the screw 23 as a fulcrum. This will carry the extension 18 away from the tip of the screw 24. When the necessary adjustment has been secured the screw 40 24 will be run in, so that its tip can firmly engage the extension 18 to thereby clamp the latter and hence securely hold the pulley 7 in its adjusted position. By the manipulation of the two screws 22 and 24, various

adjustments can be obtained; in other 45 words the pulley 7 can be swung downward or upward from its horizontal position to meet the necessary requirements and when an adjustment is obtained the proper screw will be set to maintain the same. 50

Connected with the extension 18 is the lubricator 25 which discharges at its lower end into the channel 26 having an outlet 27 opening into the groove 28 of the shaft 16 to lubricate the pulley 7. The upper wall 55 of the boxing 11 has an elongated slot 29 through which the lubricator 25 extends and which permits free movement of the lubricator 25 as the extension 18 is tipped or moved endwise in the various adjustments of the pulley 7. 60

What I claim is:

1. Pulley mechanism comprising a shaft, a pulley rotatively supported by said shaft, the latter having an extension provided 65 with flat opposite faces, a boxing to receive said extension and having flat faces adapted to be slidably engaged by those of the extension, and means for tipping the extension in the boxing. 70

2. Pulley mechanism comprising a shaft, a pulley rotatively supported by said shaft, the latter having an extension provided with flat opposite faces, a boxing to receive said extension and having flat faces slidably 75 engaged by those of the extension, two screws engaging one face of the extension, and a third screw engaging the opposite face of the extension at a point between those which the other screws engage said 80 extension, the several screws being tapped through the boxing.

In testimony whereof I affix my signature in presence of two witnesses.

BENGT M. W. HANSON.

Witnesses:
